UNITED STATES PATENT OFFICE

EDWARD BELLMAN, OF ROCKFORD, ILLINOIS

ALARM-CONTROL UNIT

Application filed November 26, 1928. Serial No. 321,929.

This invention relates to alarm control unit.

Objects of this invention are to provide a novel form of alarm control unit which is so constructed that it may be placed in a great number of different positions within a house or building, which is so made that it will cooperate with a window, door or other member which may be moved, or which may 10 operate with a wire or thread adapted to be either burned through in case of fire, pushed upon or broken in the event that it is stretched across a window or other opening, or across the wall, etc. Contact is made before the 15 wire or thread is broken if tampered with by a slight touch thereon.

Further objects are to provide an alarm control unit which is of very simple construction, which may be cheaply manufactured, and which is easily applied.

Embodiments of the invention are shown in the accompanying drawings, in which:

Figure 1 shows the form of the unit applied to a string or wire.

Figure 2 is a face view of the unit shown in Figure 1.

Figure 3 is a sectional view on the line 3—3 of Figure 2, drawn to an enlarged scale.

Figure 4 is a view showing the unit applied to a door or window and showing a different form of the unit with one form of alarm system associated with the unit.

Referring to Figures 1, 2 and 3, it will be seen that the unit comprises an insulating block 1, which may be held in place by means of spaced screws 2, and attached to any portion of the building desired. This insulating block is provided with a projecting flange 3. An L-shaped adjustable metal member 4 is secured by means of a bolt 5 to the underside of this flange. A coil spring 6 has one arm 7 thereof secured to the outer face or insulating flange 3 by means of a bolt 8.

It is to be noted that the L-shaped member 4 has one portion 9 thereof provided with an aperture 10, through which the other arm 11 of the spring member projects. This arm 11 terminates in an eyelet 12. Conductors lead from the bolts 5 and 8 to the alarm system.

In the form shown in Figure 1, the alarm

is controlled by means of a thread or wire 13 which is attached to the eyelet 12 and extends across the portion to be protected, and is attached to a screw eye 14. For instance, in case the device is used to indicate fire, the apparatus may be placed in the upper portion of the room, adjacent the ceiling, or wherever desired, and also may be associated with any opening in the house, such as a window, so that the thread or wire may be broken or touched upon a forced entry. Obviously, any number of threads or wires may be employed and may be so arranged that the breaking or touching of any one thread will free the spring arm 11 and allow it to contact with the member 9. Further, contact with the thread or wire or member 13 will move the arm 11 and cause it to contact with the member 9. In other words, any disturbance of the thread or member 13 will set off 70 the alarm by closing the circuit of this control unit.

Great flexibility is obtained as to the direction in which the thread may be run or the direction in which the arm may be moved, 75 by proper adjustment of the spring, and adjustable member 9.

In the form shown in Figure 4, the same inventive idea is employed; the insulating block is identical to that one previously described, and is provided with a flange 3. The member 4 is provided with an apertured portion 9, through which the spring arm 15 projects. This spring arm is connected to a coiled portion 16, which may lie in a plane 80 parallel to that of the insulating block 1, as described and as shown in Figure 4. The other arm of the spring is attached to the bolt 17, as shown in Figure 4. The member 4 is held in place by means of the bolt 18. The 85 bolts 17 and 18 are connected to the alarm system in a manner hereinafter to appear.

In using the device, the eyeleted outer end 19 of the spring arm 15 is arranged to bear against a door or window or a thread or wire 90 attached, such as indicated by the reference character 20, so that upon motion of this movable member, the contacts will be closed by the engagement of the spring arm 15 with the member 9.

Any suitable system may be employed in connection with these units. For instance, the bolt 18 may be connected to a conductor 19, and this conductor may lead to one contact of an electric bell 20. The other contact of the electric bell may be connected to a control or cut-out switch 21 and from thence to one side of the battery 22.

The other side of the battery is connected through the coils of the electro-magnet 23 to the conductor 24, leading to the bolt or terminal member 17. As soon as the terminal members 17 and 18 are bridged by the contact of the spring arm 15 with the member 9, current flows from the battery through the coils 23 of the electro-magnet. This electro-magnet may actuate an armature 25, which acts as a latch for a drop 26. The drop 26 may connect the wire 19 with one side of the battery 22, thus closing a local circuit, including the bell, and causing the bell to continuously sound. Obviously, other types of drop switches may be employed in the system, and other alarm devices may be employed in place of the bell.

The switch 21 may be a master switch controlled by key lock, as described in my application for burglar alarm and lock, Serial No. 321,930, filed November 26, 1928.

It will be seen that these alarm control units are very simple in construction, are easy to produce, and are very easy to apply. They have a wide variety of uses and may be associated with a thread or similar member, or with any members which are adapted to be moved. In practice, I provide a cover as a protector to be placed upon these units that cannot be removed without forming a contact.

Although this invention has been described in considerable detail, such description is intended as illustrative rather than limiting, as the invention may be variously embodied and as the scope of such invention is to be determined as claimed.

I claim:

1. An alarm control unit comprising a body portion formed of insulating material and having a projecting lip, a metal bracket secured to one side of said projecting lip and extending outwardly therefrom and terminating in an apertured end, a spring arm having one end secured to said insulating bracket and having the other end projecting outwardly through the aperture in said bracket and terminating in an eyelet.

2. In an alarm control unit, comprising a body portion formed of insulating material and having a longitudinal projecting flange at one end thereof, an L-shaped member having its stem portion adjustably connected to the flange on the insulated body, the lateral portion of said L-shaped member being spaced from the outer extremity of the flange and formed of an aperture, a coil spring member positioned between the lateral portion of

the L-shaped member and the flange with one arm on the spring removably connected to the flange and the other arm on the spring extending through the aperture in the lateral portion of the L-shaped member, an eyelet formed at the outer end of the second arm on the spring and means cooperating with the eyelet for normally maintaining the second arm out of contact with the lateral portion of the L-shaped arm.

In testimony that I claim the foregoing I have hereunto set my hand at Rockford, in the county of Winnebago and State of Illinois.

EDWARD BELLMAN.
